UNITED STATES PATENT OFFICE.

NELSON J. RUSSELL, OF CHICAGO, ILLINOIS.

FUEL-SAVING ATTACHMENT FOR FURNACES.

1,205,789.

Specification of Letters Patent. Patented Nov. 21, 1916.

Application filed May 1, 1916. Serial No. 94,611.

To all whom it may concern:

Be it known that I, NELSON J. RUSSELL, a citizen of the United States, and resident of Chicago, in the county of Cook and State of Illinois, have invented certain new and useful Improvements in Fuel-Saving Attachments for Furnaces, of which the following is a specification.

This invention relates to improvements in a device adapted for use in connection with furnaces, stoves or ranges, for pre-heating air and discharging or distributing said heated air into the fire-pot or fire-space, to the end, that more perfect combustion may be attained, and it consists in certain peculiarities of the construction, novel arrangement and operation of the various parts thereof as will be hereinafter more fully set forth and specifically claimed.

The main object of the invention is to provide an extremely simple and inexpensive device for automatically admitting, heating and discharging or distributing atmospheric air into furnaces, such as stoves, ranges, bake-ovens, boiler-furnaces, and the like, in such a manner that the supply of air to the furnace, will, through the medium of the device, be heated to a high degree of temperature, and in such condition discharged or distributed in the furnace, and by preference, in the fire-box or pot thereof, to commingle with the combustible and volatile gases emanating from the burning fuel, where said heated air and oxygen will be utilized to increase from a given amount of fuel, the combustion of the combustible gases, or of the free carbon released during the burning of such fuel, thereby avoiding, to a marked degree, the formation of smoke, yet attaining the maximum amount of heat units from the fuel, for it is a well known fact that smoke is due to a lack of air at the proper temperature at the point where the volatile gases should be consumed.

Another object of the invention is to provide an attachment of the above described general character, which, if desired, can be readily attached to the door of the stove, furnace, or range, leading to the fire-box thereof, and used in connection with said door, in such a manner that it will not interfere with the opening or closing of the door, or with feeding fuel to the grate of the fire-box, or if desired, said attachment may be mounted within the furnace in a stationary or immovable manner.

Other objects and advantages of the invention will be disclosed in the subjoined description and explanation.

In the accompanying drawing which serves to illustrate an embodiment of the invention—Figure 1 is a view partly in section and partly in elevation of a fragment of the fire-box or fire-space of a furnace, stove or range, showing a fuel saving attachment embodying my invention mounted upon the door thereof and located in position for use. Fig. 2 is an enlarged plan sectional view taken on line 2—2 of Fig. 1 looking in the direction indicated by the arrows. Fig. 3 is a vertical sectional view taken on line 3—3 of Fig. 2 looking in the direction indicated by the arrows, and Fig. 4 is a reduced fragmental sectional view taken on line 3—3 of Fig. 2, showing a modification in the construction of the expansion chamber of the device.

Like numerals of reference refer to corresponding parts throughout the different views of the drawing.

The numeral 5 designates a portion of the front wall of a stove, range or furnace, which may be of the ordinary or any preferred construction, but as usual, is provided with a fire-box 6 in the lower portion of which is located a grate 7 on which the coal or other fuel 8 is placed for consumption through a doorway 9 formed in the front wall or portion of the furnace, oven or range. Mounted on the outer surface of the front wall of the fire-box, in the usual manner, is a door 10 which is provided centrally with an opening 11, around which opening is located and secured by means of bolts 12, a flange 13 on the front part of the receiving chamber or box 14 of the attachment or device, which consists of a horizontally disposed member or plate, which is designated as a whole by the reference numeral 15, and which is, by preference, of a size to permit it to pass back and forth through the opening or doorway 9 in the front wall of the furnace when the door 10 thereof is opened or closed.

As is clearly shown in Figs. 2, 3 and 4 of the drawing, the horizontally disposed plate or member 15 is provided with a convolute conduit or passageway 16 which communicates at one of its ends with the box or receiving chamber 14 and at its other end with an expansion and discharging chamber 17 which is, by preference, substantially spheri-

cal in shape as shown, and is about equally divided by the plate or member 15, so that one of its portions will extend above said plate or member, while its other portion will 5 extend below the same. By reference to Figs. 2, 3 and 4 of the drawing, it will be seen that the end of the conduit 16, which communicates with the discharging chamber 17 is contracted as at 18, thus forming a 10 throat for the purpose to be presently explained. The upper portion of the chamber casing 17 is provided with a vertical slot 19 for the passage of heated air, and the casing of the chamber 17 is provided in its lower 15 portion with a downwardly enlarged opening 20, which, under certain conditions, or at certain times, is also employed for the passage of heated air from the attachment.

In Fig. 4 is illustrated a modification in 20 the construction of the casing of the expansion or discharging chamber, which consists in providing the casing or chamber 17 in its upper and lower portions with slots 19 of about equal size, instead of forming the 25 lower slot larger than the upper one, as is shown in the other views of the drawing and above described. Otherwise, the modified construction shown in Fig. 4 is identically the same as that above shown and described.

30 The operation of the device is simple, and as follows: The receiving box or chamber 14 of the horizontally disposed plate or member 15 is secured to the inner surface of the door 10 of the furnace, stove or range, and around an opening 11 therein so that atmospheric air can pass through said opening in the door and into the box or chamber 14, from whence it will pass through the convolute conduit 16 in the direction indicated by the arrows in Fig. 2 of the drawing. It will be understood that the device is located horizontally within the fire-box of the furnace and above the fuel on the grate thereof, in about the position 40 shown in Fig. 1 of the drawings, and it is obvious that when the fire is started, and the fuel begins to burn on the grate, some of the heat will pass into the enlarged opening 45 of the expansion chamber 17 and out 50 through the slot 19 in the upper portion of said chamber, thus creating a draft therethrough, which will produce suction at the reduced and communicating end 18 of the conduit 16, to the end, that a free circulation 55 of air will be created through said conduit, which air will be heated in this passage by means of the heat from the fuel on the grate. Now, as the fire increases in intensity, naturally the draft of the flue or chimney of 60 the stove or furnace will cause the heat from the fuel to travel rearwardly and beyond the rear portion of the member 15, in which operation it is obvious that the heated air within the conduit 16 of the attachment 65 will be discharged from the expansion cham-

ber 17 through the opening 19, as well as through the opening 20 thereof and will be forced rearwardly to commingle with the volatile and combustible gases in the firebox, and especially at the rear portion of 70 the attachment. When the modified construction shown in Fig. 4 is employed, practically the same operation and result is attained except that the slot 19 in the lower portion of the expansion chamber 17 will not 75 act so much as an upwardly extended flue for the heat from the fuel when the fire is first started, as will the enlarged opening 20 shown in the other construction.

It will be observed by reference to Fig. 3 that the convolutions of the conduit 16 are connected by comparatively thin webs 21 which will permit said convolutions to be almost entirely exposed to the heat of the furnace, to the end, that the air passing 85 through the conduit will be quickly heated.

In order to strengthen the device at its front portion, the receiving box or chamber 14 may be connected to the front part of the member 15 on each side thereof by means 90 of a rib or web 22 which will also serve in connection with the member 15 as a baffle plate in the upward progress of the heat from the flue.

Having thus fully described my invention 95 what I claim as new and desire to secure by Letters Patent is—

1. In a fuel saving attachment for furnaces, the combination with a furnace having a combustion chamber and an opening 100 leading thereto, of a plate or member having a receiving chamber-casing mounted in communication with said opening and within the combustion chamber, said plate or member being horizontally disposed and 105 provided about centrally thereof with a hollow enlargement having in its upper and lower portions each a transversely extended opening, the said plate or member also having a convolute conduit communicating at 110 one of its ends with said receiving chamber and at its other end with said hollow enlargement.

2. In a fuel saving attachment for furnaces, the combination with a furnace having a combustion chamber and an opening 115 leading thereto, of a plate or member having a receiving chamber-casing mounted in communication with said opening and within the combustion chamber, said plate or member being horizontally disposed and 120 provided about centrally thereof with a hollow enlargement having in its upper and lower portions each a transversely extended opening, the opening in the lower portion 125 of said enlargement being outwardly flared, the said plate or member also having a convolute conduit communicating at one of its ends with said receiving chamber and at its other end with said hollow enlargement. 130

3. In a fuel saving attachment for furnaces, the combination with a furnace wall having a doorway, of a hinged door therefor, said door having an opening therein leading to the combustion chamber of the furnace, a plate or member having a receiving chamber-casing mounted on the inner surface of the door in communication with the opening therein, said plate or member being horizontally disposed and provided about centrally thereof with a hollow enlargement having in its upper and lower portions each, a transversely extended opening, the said plate or member also having a convolute conduit communicating at one of its ends with said receiving chamber and at its other end with said hollow enlargement.
4. As a new article of manufacture, a plate or member having at its edge a receiving chamber-casing and provided with a convolute conduit leading from said chamber-casing to the central portion of said plate or member and having its inner end contracted; a hollow enlargement on the central-portion of the said member in communication with said conduit and having in its upper portion a slot extended in parallelism with said chamber casing and in its lower portion a downwardly enlarged opening.

NELSON J. RUSSELL.
